DESIGN FOR A COAT

Abe Gruber, New York, N. Y.

Application June 18, 1945, Serial No. 120,172

Term of patent 3½ years

(Cl. D3—4)

To all whom it may concern:

Be it known that I, Abe Gruber, a citizen of the United States of America, residing in New York city, county of Kings, and State of New York, have invented a new, original, and ornamental Design for a Coat, of which the following is a specification, reference being had to the accompanying drawing, forming part thereof, wherein,

I claim:

The ornamental design for a coat, substantially as shown.

ABE GRUBER.
